said openings, a drain from the upper side of said partition, a forwardly inclined ice cake supporting plate mounted in said ice chamber over said partition, said plate having relatively deep front-to-
5 rear corrugations providing one upwardly open set and one downwardly open set of channels, the front portions of the downwardly open channels being adapted to receive and forwardly conduct the aforesaid ascending warm air and having
10 their front ends open to discharge this air in front of the ice cake, all of the upwardly open channels not covered by the ice cake being adapted to receive and rearwardly conduct cold air descending at the sides of the ice cake, the rear portions
15 of the bottoms of said upwardly open channels having longitudinally spaced openings through which the cold air escapes to the cold air-conducting opening of said partition.
6. A refrigerator comprising a casing, a sub-
20 stantially horizontal partition dividing said cas-
ing into an upper ice chamber and a lower food
chamber, the edges of said partition being secured
to the casing, said partition having an upwardly
25 directed front portion in spaced relation with the
casing front wall, said upwardly directed portion
having conducting openings for ascending warm
air, the rear portion of said partition being pro-
vided with a conducting opening for descending
cold air, means for preventing ice drippings from
30 passing through any of said openings, a drain
from the upper side of said partition, a forwardly
inclined ice cake supporting plate mounted in said
ice chamber, said plate having relatively deep
front-to-rear corrugations providing one up-
wardly open set and one downwardly open set of
35 channels, the front portions of the downwardly
open channels being adapted to receive and for-
wardly conduct the warm air ascending from said
warm air conducting openings of said partition
and having open front ends for discharging this
air in front of the ice cake, all of the upwardly
open channels not covered by the ice cake being
adapted to receive and rearwardly conduct cold
air descending at the sides of the ice cake, the
rear portions of said upwardly open channels
40 having escape openings for the cold air descend-
ing to said cold air-conducting opening of said
partition.

REFRIGERATOR

William Mauthe, Fond du Lac, Wis., assignor to
 Sanitary Refrigerator Company, Fond du Lac,
 Wis., a corporation of Wisconsin

Application December 18, 1933, Serial No. 702,988

6 Claims. (Cl. 62—46)

The invention relates to a refrigerator using ice as a cooling medium, and it aims to provide a new and improved structure in which air is so circulated that it ascends in the front of the food chamber, enters the ice chamber, flows upwardly in front of the ice cake, then flows over the top of the ice and down the sides of the same, descends into the food chamber and finally flows downwardly in the latter to start another cycle 10 of circulation. In so circulating not only is the air thoroughly chilled to produce effective refrigeration, but it is virtually washed by contact with the melting ice and is thus freed from impurities. Moreover, repeated opening of the 15 food chamber door will not materially change the efficiency of the refrigerator, for any warm air entering through the open door, immediately ascends and hastens the circulation.

Fig. 1 is a vertical sectional view cut in a plane 20 at right angles to the refrigerator front.

Fig. 2 is a horizontal sectional view on line 2—2 of Fig. 1.

Fig. 3 is a front elevation with the ice chamber and food chamber doors removed, parts of this 25 view being shown in vertical section on the plane of line 3—3 of Fig. 1.

Fig. 4 is a perspective view of the corrugated ice supporting rack.

Fig. 5 is a perspective view of a shield herein- 30 after described, which is instrumental in preventing any descent of drip water from the melting ice into the food chamber.

While the form of construction selected for illustration will be rather specifically described, 35 it is to be understood that within the scope of the invention as claimed, numerous variations may be made.

An appropriate insulating casing C is shown, 40 provided with a lower door D into a food chamber F and with an upper door D' into an ice chamber I. The two chambers are separated by a partition 10 which, while substantially horizontal, declines slightly toward the rear, at which a drain 11 is located. The partition 10 is pro- 45 vided with a vertically directed front portion 12 which is rearwardly spaced from the front wall of the casing C, said upwardly directed portion being provided with a multiplicity of openings 13 to conduct ascending relatively warm air into 50 the lower portion of the ice chamber I. The back edge and the front-to-rear edges of the partition 10 are fluid-tightly secured to the refrigerator lining 14, and the front edge of said partition (at the upper end of the portion 12) 55 may well be provided with a flange 15 secured

upon a cleat 16 secured to the front wall of the casing, between the upper and lower doors. A downwardly and rearwardly curved cowl 17 extends over the openings 13, to prevent any descending drip water from passing through these 60 openings into the fluid chamber F.

The rear portion of the partition 10 is formed with a relatively large opening 18 to conduct descending relatively cold air. This opening 18 is surrounded by an upstanding flange 19 which 65 prevents any of the drip water on the upper side of the partition 10 from flowing into said opening, and to prevent any of such water from dropping directly through the opening, a suitable shield 20 is provided above the same. In the 70 present showing, this shield is provided with forwardly projecting supporting arms 21 which rest upon the front part of the cowl 17, which part is supported by the ledge 16 and flange 15, in the present showing. I have shown suspending hooks 75 22 at the rear of the shield 20, resting upon a rear ledge 23 in the casing C.

A novel ice supporting rack is mounted over the partition 10 and shield 20. This rack is formed from a corrugated metal plate 24 secured by 80 welding or the like to front and rear bars 25 and 26 which, in the present showing, rest upon the arms 21 and the hooks 22 respectively. The corrugations of the plate 24 are unusually deep, 85 as compared to conventional corrugated plates for supporting ice cakes, and said corrugations, provide the plate with an upwardly open set of channels 27, and with a downwardly open set of channels 28, all of said channels extending from front to rear. All ascending relatively warm air 90 passing through the openings 13 and under the cowl 17, enters the front portions of the downwardly open channels 28 and is forwardly directed by these channels, into the space in front of the ice cake or block B. The front ends of 95 all of the channels 28 are open to allow escape of the ascending air therefrom and in the present showing, the upper front portions of the arched corrugations of the plate 24, are cut away as at 29, allowing free discharge of air from said channels 28. 100

The air ascending in front of the ice cake B flows rearwardly and laterally over the same and then descends at opposite sides of the ice. Any of the upwardly open channels 27 which are not 105 completely covered by the ice block B will receive this downwardly flowing cold air and will direct it rearwardly. Then too, some of this air can descend in spaces 30 which are preferably left between the plate 24 and the sides of the casing 110
